UNITED STATES PATENT OFFICE.

VICTOR HOLMSTROM, OF DETROIT, MICHIGAN.

COLLAPSIBLE BOAT.

1,359,806.

Specification of Letters Patent. Patented Nov. 23, 1920.

Application filed November 20, 1919. Serial No. 339,494.

To all whom it may concern:

Be it known that I, VICTOR HOLMSTROM, a citizen of Finland, residing at Detroit, in the county of Wayne and State of Michigan, have invented certain new and useful Improvements in Collapsible Boats, of which the following is a specification.

This invention relates to small boats, such as canoes and the like and one that may be 10 collapsed and folded.

The object of the invention is to provide a boat that may readily be folded when not in use and which can be easily carried about by hand from place to place and be stored 15 away in a comparatively small space.

A further object of the invention is to provide a boat, the bow and stern of which may be folded inward and the sides collapsed and locked together so as to completely 20 conceal the bow and stern between the sides.

A further object of the invention is to provide a collapsible boat which when in folded position will have the general appearance of a satchel, suitcase or the like.

25 A still further object is in the provision of means for holding the vessel rigid when in extended or open position.

Other objects and aims of the invention, more or less specific than those referred to 30 above, will be in part obvious and in part pointed out in the course of the following description of the elements, combinations, arrangements of parts and applications of principles, constituting the invention; and 35 the scope of protection contemplated will be indicated in the appended claims.

In the accompanying drawing which is to be taken as a part of this specification, and in which I have shown a merely preferred form of embodiment of the invention:—

Figure 1 is a plan view of my improved boat, a portion of which appears in section, Fig. 2 is a longitudinal sectional elevation of the same, Fig. 3 is a cross sectional elevation of the same showing it expanded and Fig. 4 is a perspective view of the same folded.

Referring to the drawing for a detailed 50 description of the structure illustrated, to the ends of the bottom keel bars 2 and 3 two end bars, 4 and 5, which form the bow and stern, are hinged by hinge 11. Between these bars a canvas or waterproof covering 55 A is secured by rivets or suitable means. Rigidly secured to the upper edges of the

center portion of the boat are longitudinal bars 1, while pivotally secured to the forward and rear portion of the bow and stern respectively at 16 are arcuate bars 15. The 60 covering A is secured about the bars 1 while at the bow and stern portions it is simply stretched across as suggested in Figs. 1 and 3. Hingedly secured to the opposite longitudinal sides of the keel portion 2 by hinges 65 12 are a series of ribs 6, the free ends of which are adapted to snugly fit beneath the longitudinal side bars 1. To the upper end of these ribs is secured a keeper 17 and to the free end of the bars 15 is secured a 70 spring pressed sliding latch 17 that engages with the keeper. Adjacent the upper end of the ribs and pivotally secured thereto by means of screw eyes 13 or any other suitable connection is a transversely arranged brace 75 bar 9. The other end of these transverse braces is fastened to the ribs on the opposite side of the boat by a latch member 14. Timbers or uprights 10 are hinged at their lower ends to the inner side of the keel by hinges 8. 80 These uprights are pivoted so as to fold inward and are prevented from backward movement by contacting with the surface of the keel. The upper end of these uprights is notched to engage with the transverse 85 braces and thus forms a support for said braces. Snugly fitted against the inner side of the covering and arranged between and secured to the ribs 6 are longitudinal side ribs 7 which constitute spacing and bracing 90 members for said ribs 6.

From the foregoing it will be seen that when the boat is in opened or extended position that the bars 15 will lie substantially in a longitudinal plane and that the free 95 end of these bars will lockingly engage the upper end of the ribs 6. The transverse bars will brace the sides of the vessel and be supported by the upright members 10.

To fold the boat all that is necessary is to 100 release the lock 17. Thereupon the top bars 15 will drop within the vessel. Then by releasing the latch 14 which permits the transverse members 9 to be swung longitudinally beneath the side bars 1 and folding the upright timbers 10 inwardly against the keel 2 and 3 the said bow and stern portions may be folded inwardly beneath the sides of the vessel. These sides may then be folded inwardly thereby embracing the infolded ends 110 as clearly suggested in Fig. 4 of the drawing, in which it will be seen that the com-

pacted vessel has the general appearance of a satchel or suitcase. In order that the parts may be held in this collapsed position there is provided a coöperating lock 18, secured 5 to the upper edge of the sides. Suitable handles as indicated at 19 are also provided for carrying the collapsed vessel from place to place.

As many changes could be made in this 10 construction without departing from the scope of the following claims it is intended that all matter contained in the above description or shown in the accompanying drawing shall be interpreted as illustrative 15 only and not in a limiting sense.

Having thus described my invention what I claim as new and desire to secure by Letters Patent is:

1. A boat of the class described, having a 20 keel portion, bow and stern portions hinged to said keel, collapsible side members hinged to the keel, transverse bars hinged at one end to the side of the vessel and adapted to embrace the opposite side thereof, hinged 25 uprights secured to the keel for supporting the transverse bars, and pivotally secured bracing bars within the bow and stern portions adapted to coöperate with the upper portion of the collapsible sides for sustaining 30 said bow and stern in extended position.

2. A boat of the class described, having a 35 keel portion, bow and stern portions hinged to said keel, collapsible sides hinged to said keel, a longitudinal bar secured to the upper edge of said collapsible sides, bracing bars having one end pivotally secured to the up-

per end of the bow and stern the free end of said bars having locking engagement with the longitudinal bars, the bow and stern arranged for folding inwardly above 40 the keel, the sides of the boat adapted to be collapsed upon the bow and stern, means for holding the boat locked when in collapsed position and handles secured to the longitudinal bars for carrying the boat. 45

3. A boat of the class described, having a keel portion, bow and stern portions hinged to said keel, collapsible sides hinged to said keel, a longitudinal bar secured to the upper edge of said collapsible sides, bracing 50 bars having one end pivotally secured to the upper end of the bow and stern, the free end of said bars having locking engagement with the longitudinal bars, the bow and stern arranged for folding inwardly 55 above the keel, the sides of the boat adapted to be collapsed upon the bow and stern and means for holding the boat in collapsed position with the longitudinal bars abutting each other. 60

4. A boat of the class described, having a keel portion, bow and stern portions hinged to said keel, collapsible sides hinged to said keel, bracing bars having one end pivotally secured to the upper end of the bow and 65 stern, the free end of said bars having locking engagement with the upper portion of the collapsible sides for sustaining said bow and stern in extended position.

In testimony whereof I affix my signature. 70

VICTOR HOLMSTROM.
